Stalter, St. Paul, Minn.
The subscriber resides in these letters, D. Stalter, and making part of the same,
containing a description of the works of the said, late D. Walker himself,
of his improvement in the Hydrant for drawing Water.
To all to whom these presents shall come, Be it known, That I, D. Stalter,
of Walker of the city, & county of Baltimore, State of Maryland, have
invented, or now improved, in "the Hydrant for drawing Water,"
which hydrant I have already patented in accordance of the Act of the 3d of
March, in the year eight hundred and thirty five, and that the
following is a full and exact description of the construction & operation of
the said improvement as invented by me. The said invention consists
of a valve case, which will be occasionally cast, and will surround the
water's pipe to afford them the requisite protection. It is also, made for
the purpose of maintaining the distance between the upper and lower
ends of the valve, but they should be separated by frost or other cir-
cumstances. The descending tubes from the supply pipe from which
the water is discharged, is supported by means of a wooden
log, according to my old mode of construction, but I have adopted
a cast iron case, with openings in rear or side of its sides, at the latter
in bottom, for the purpose of affording the water at the lower end,
when necessary, to be admitted to the valve
case or valve. The spear or shaft described in my former patent,
as passing down from the top of the hydrant to the valve seat, has
a sleeve or rod support which passes into or through a case of platin
or the covering affixed to the upper end of the case in case, and con-
taining the spear, as usual the valve is raised, or closed, I insert
the valve into the valve, when shall be made within the opening in the case
case under pressure and then off the valve according to my former plan
When I have the lining of demineralized substance, in the valve case in
the valve seat, I generally for greater durability, introduce, with lead, wax
and apply it to the hydrant, or supply pipe, by attaching it
firmly to the body or plug of the valve. When I use a demineral-
ized water as an ordinary water for the use of the supply pipe and valve
is separated within the case, I make the discharge pipe

the cock to turn upwards within the body of the case, and from it is a hole and lead to receive the spigot end of the ascending pipe to which is attached his or her neyler for the discharging of the water by, so as to be able to attach the or her hole to the same plug, or for the purpose of having a convenient mode of attachment at or near the surface of the ground, it also answers in this case to increase the head of water, and removes the possibility of obstruction of the flow of water, from a hindrance that might otherwise be in the hole when elevated. To the other end of the cock it goes a hole and connects it to the supply pipe by a circular pipe intended for the purpose of raising the front of the case, and the discharging pipe, so as to discharge the water in the same direction it has received from. In the coupling joint for connecting the pipe, as in any old patent, for the purpose of offering a ready means of detaching them from the cock or valve seat. It preserves at all times the same distance between the upper and lower ends of the works, to prevent separation by frost or other circumstances, as before stated, the cock or valve seat, is placed, in the opening in the lower end of the iron case, and the seat plate, or covering, in which the spear or shaft works, which is used for holding the valve, is likewise shown, for turning the plug of the cock, has a screw cut in it, it passes into it the iron or the upper end of the spear, where the lever is attached. What I claim as my invention, and for which I now ask Letters Patent, is the construction and use of a certain case for the purpose of maintaining the distance necessary, either with or without the valve plug, with the iron case for protecting the other works of the implement, from the plug, from injuries. But when it is not necessary according, it is plain around the other works without the construction for maintaining the distance, that the confining down of the top by means of seven bolts and nuts, intended to assist in easing and tightening the works. Likewise providing neyler conveniently to the discharging pipe for shifting policy before it is turned, in disconnecting the plug, also for the purpose of using a circular pipe to the plug for raising the neyler or front of the discharging pipe, and
